Primary Examiner — Cynthia Ramirez*Assistant Examiner* — Jeremy S. Swartz(74) Attorney, Agent, or Firm — Tommy SF Wang; Wang IP Law Group, P.C.(57) CLAIM

The ornamental design for a cabinet organizer, as shown and described.

DESCRIPTION

FIG. 1 is a perspective view of a cabinet organizer showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in FIGS. 1–7 are for the purpose of illustrating portions of the cabinet organizer that form no part of the claimed design.

1 Claim, 7 Drawing Sheets(56)
